Inventor,
Henry W. Warner,
By his Attorney
W. L. Bailey.

UNITED STATES PATENT OFFICE.

HENRY W. WARNER, OF BALTIMORE, MARYLAND.

CAR-COUPLING.

SPECIFICATION forming part of Letters Patent No. 393,492, dated November 27, 1888.

Application filed April 10, 1888. Serial No. 270,208. (No model.)

To all whom it may concern:

Be it known that I, HENRY W. WARNER, a citizen of the United States, residing at Baltimore, in the State of Maryland, have invented 5 certain new and useful Improvements in Car-Couplers; and I do declare the following to be a full, clear, and exact description of the invention, such as will enable others skilled in the art to which it appertains to make and use 10 the same, reference being had to the accompanying drawings, and to the letters and figures of reference marked thereon, which form a part of this specification.

My invention relates to improvements in automatic car-couplings; and it consists of certain devices whereby the couplings of two cars will be automatically locked when brought together, and in certain other devices whereby the said couplings will be automatically released by the movement of a lever from the side of the cars, to accomplish all of which I employ the devices hereinafter fully described and claimed, reference being had to the accompanying drawings, in which—

25 Figure 1 shows a part of two cars which are coupled by this device. Fig. 2 is a view looking down on a pair of couplings in the locked position, one coupling being shown in section indicated by the line C C, Figs. 3 and 4. Fig. 3 shows a cross-section through the device indicated by the line A A, Figs. 2 and 4. Fig. 4 shows a vertical section through the device indicated by the line B B, Fig. 3, the tongue being shown in full and in the closed position. Fig. 5 is a 35 view in full looking down on the device in the open position. Fig. 6 is a horizontal section of the device, the section being indicated by the line D D in Fig. 3, the tongue shown full and in the open position. Fig. 7 is a detailed 40 side elevation of the tongue shown in full, with the common link and link-pin connected therewith.

The same figures refer to the same or similar parts throughout the several views.

45 The figure 8 denotes the platform of a car, under which is suspended by a strap, 9, the coupling, a draft-rod, 10, connecting the coupling of each end of the car in the usual manner, and a buffer, 11, backed by the beam 12, 50 serving to relieve the shock of impact. The bull-nose 13, which contains the locking mech-

anism, is provided with a rectangular recess, 14, which conforms in size and shape to the inner end, 15, of the tongue 16, whereby the said tongue may be freely moved in and out 55 of the bull-nose and perform its necessary functions, a larger recess, 17, being provided in the back of the bull-nose to lessen its weight and to provide for the attachment thereto of the draft-rod 10. The tongue 16 is constructed 60 in the form shown in Figs. 6 and 7, the outer end, 19, being provided with an offset, 18, for locking into a corresponding offset of the tongue of another coupling, this offset end being made in a curved or beveled form to 65 facilitate its adjustment to the other coupling, and is also made of sufficient depth to insure a secure hold of the two tongues when the couplings of the two cars may be at different heights, and whereby a universal movement 70 between the couplings is permitted by this construction. This widest part of the tongue is carried back and forms an offset, 20, which stops the inward movement of the tongue within the bull-nose, and thus prevents injury to 75 the locking mechanism within the device.

When the tongue 16 has been moved to the full extent of its movement in the bull-nose, it is secured in this position by the lock-plate 21, which is free to move vertically in the slot 80 22, which is provided therefor in the casting of the bull-nose, the said lock-plate 21 being raised by the tapered end 32 in the inward movement of the tongue and engaging with the locking slot 23, with which the inner end of the 85 tongue is provided on the upper side thereof, whereby the tongue will be securely held in this inner position, a lever, 24, which is operated by the shaft 25, and the hand-lever 26 serving to disengage the lock-plate 21 from 90 the slot 23 of the tongue, and thus permit the tongue to be drawn outward.

In order that the outward movement of the tongue may be stopped, and that it may be caused to move out of a straight line and to 95 the position shown in Figs. 5 and 6, there is provided the stop-plate 27, which is rigidly secured in some suitable manner to the bull-nose, the said stop-plate passing through the guide-slot 29, with which the tongue is provided, 100 that part of the stop-plate 27 which is in the said slot 29 having thereon the projecting in-

clined edge 28, whereby when the inner end, 30, of the guide-slot 29 comes in contact with the said inclined edge 28 it will be thrown to one side and the locked offset ends 18 of the 5 tongues released, the bull-nose having therein an enlargement, 31, to the recess 14 to permit this deflected movement of the tongue.

In Figs. 5 and 6 the device is shown in the open position preparatory to coupling. When 10 the two couplings are brought together, the end 19 of the tongue will strike the bull-nose of the opposite coupling and be thereby forced inward, the form of the recess 14, in which the tongues move, causing the ends 19 to be brought 15 together and the offsets 18 thereof interlocked one with the other, as stated, this inward movement of the tongue causing the lock-plate 21 to be raised by the tapered end 32 thereof and engage with the locking-slot 23 therein, thus 20 securely holding the offset ends 19 of the couplings in this interlocked position, the form of the said offsets 18 permitting a limited movement of the two couplings, one to the other, in a horizontal plane, and their extreme depth 25 permitting a movement in a vertical plane, thus permitting a universal movement between the couplings.

When it is desired to uncouple the cars, the lock-plate 21 is raised by means of the lever 30 26, this operation being performed on each car, which will permit the tongues 16 to be drawn outward, and by the operation described the ends 19 of the tongues will be thrown apart and the offsets 18 of the respective 35 couplings released from each other, and the couplings be in the positions shown in Figs. 5 and 6, gravity causing the lock-plate 21 to remain normally in the down position and the couplings in condition to automatically couple.

In order to further relieve the shock of collision on the couplings, the tongues may be provided with the projections 33, placed on the outerside thereof, which will be caught between the bull-noses of the couplings, and 45 thus take the shock.

To provide means to couple to another car which is not provided with a device of this

description, the end 19 of the tongue 16 is provided with a recess, 36, therein to accommodate an ordinary coupling-link, 35, which is held in position by the link-pin 34, which passes vertically through the end 19 of the tongue.

Having described my invention and the 55 manner of operating, what I claim, and desire to secure by United States Letters Patent, is—

1. In a car-coupling, the combination of a bull-nose, a tongue free to be moved in or out 60 of the said bull-nose, said tongue provided with a slot, 29, and offset 18, a stop-plate, 27, provided with the inclined projecting edge 28, whereby the said tongue will be caused to move out of a straight line, and mechanism 65 for locking the said tongue in the inner position, for the purpose set forth.

2. In a car-coupling, the combination of a bull-nose provided with the rectangular recess 14, with the enlarged space 31 therein, a 70 tongue, 16, free to be moved in or out of the said bull-nose, the said tongue provided with the guide-slot 29, the offset 18, and the locking-slot 23, the stop-plate 27, provided with the inclined projecting edge 28, whereby the 75 said tongue will be caused to move out of a straight line, and a lock-plate, 21, to engage with the slot 23 of the tongue, for the purpose set forth.

3. In a car-coupling, the combination of a 80 bull-nose, the tongue 16, free to be moved in or out of the said bull-nose, said tongue provided with a guide-slot, 29, a locking-slot, 23, an offset, 18, and a recess, 36, in the offset end thereof, a link-pin, 34, a stop-plate, 27, 85 with the inclined projecting edge 28 thereon, whereby the said tongue will be caused to move out of a straight line, and the lock-plate 21, to engage with the locking-slot 23 of the tongue, for the purpose set forth.

In testimony whereof I affix my signature in presence of two witnesses.

HENRY W. WARNER.
